(57) **ABSTRACT**

If closing operation to the passenger's seat sub switch continues for not less than a prescribed time period Tb, a passenger's seat relay contact on a close side is turned ON. If the closing operation to the passenger's seat sub switch thereafter ends before a prescribed time period Tc elapses, the passenger's seat relay contact on the close side is kept ON. If opening operation to the passenger's seat sub switch continues for not less than the prescribed time period Tb, a passenger's seat relay contact on an open side is turned ON. If the opening operation to the passenger's seat sub switch thereafter ends before the prescribed time period Tc elapses, the passenger's seat relay contact on the open side is kept ON. The invention is applicable to an automatic window system and the like.

**WINDOW OPENING-CLOSING CONTROL
SYSTEM AND WINDOW
OPENING-CLOSING CONTROL APPARATUS**

**CROSS-REFERENCE TO RELATED
APPLICATION**

This application is based on Japanese Patent Application No. 2014-131166 filed with the Japan Patent Office on Jun. 26, 2014, the entire contents of which are incorporated herein by reference.

FIELD

The disclosure relates to a window opening-closing control system and a window opening-closing control apparatus, and particularly relates to a window opening-closing control system and a window opening-closing control apparatus configured to open and close windows at vehicle seats in addition to a driver's seat at the driver's seat.

BACKGROUND

In an automatic window system configured to open and close a vehicle window with an electric motor, the motor rotates positively or negatively in accordance with a state of operation to an operation switch, to open or close the window. For example, the motor rotates positively to close the window if the operation switch is operated to a close side (an UP side) whereas the motor rotates negatively to open the window if the operation switch is operated to an open side (a DOWN side). Positive and negative rotation of the motor is controlled by switching a direction of current flowing to the motor at a motor driving circuit in accordance with a signal transmitted from the operation switch.

An automobile is typically equipped with operation switches at a driver's seat and other seats (a front passenger's seat, a rear right passenger's seat, a rear left passenger's seat, and the like). The operation switch at the driver's seat (main switch) includes a driver's seat switch configured to open and close a driver's seat window as well as passenger's seat switches each configured to remotely open and close a corresponding one of passenger's seat windows. The operation switch at each of the passenger's seats (sub switch) is configured to open and close only the corresponding passenger's seat window. There is further provided a controller configured to control opening and closing the windows in accordance with operation to the main switch and the sub switches.

Window opening-closing control includes control to open or close a window only while an operation switch is operated (manual motion) and control to open or close a window until the window is entirely opened or closed even if operation is stopped (automatic motion). An operation switch for automatic motion of the driver's seat window is typically provided only with the main switch whereas each of the sub switches is provided only with an operation switch for manual motion.

JP 2008-19625 A discloses a window opening-closing control apparatus that includes controllers provided respectively to a main switch at a driver's seat and sub switches at passenger's seats, and the controller for each of the seats is configured to control manual motion and automatic motion of a window at the corresponding seat. The controllers for the respective seats are connected via a serial communication line in the window opening-closing control apparatus. If the driver's seat main switch is operated to open or close one

2

of passenger's seat windows, the controller for the driver's seat communicates to the controller for the corresponding seat via the serial communication line and the controller for this seat controls to drive a motor.

JP 06-343279 A discloses a window opening-closing control apparatus that includes a single controller configured to control a driving motor for a window at each seat in response to input to a main switch at a driver's seat or to a sub switch at each passenger's seat. The sub switch at each passenger's seat is provided with an automatic switch. Operation to the automatic switch enables a window at the passenger's seat to open and close automatically.

SUMMARY

One or more embodiments of the disclosure provide a window opening-closing control system and a window opening-closing control apparatus configured to automatically open and close a window at a passenger's seat with an operation switch that is provided at the passenger's seat, includes a contact for manual operation, and is not provided with any member for automatic operation.

One or more embodiments of the disclosure provide a window opening-closing control system configured to control opening and closing a window at a driver's seat and a window at a passenger's seat other than the driver's seat in a vehicle, the window opening-closing control system including: a passenger's seat unit provided at the passenger's seat; and a window opening-closing control apparatus provided at the driver's seat and configured to control a driver's seat motor configured to open and close the window at the driver's seat and a passenger's seat motor configured to open and close the window at the passenger's seat; the passenger's seat unit including: a momentary passenger's seat sub switch having a first contact operated to close the window at the passenger's seat and a second contact operated to open the window at the passenger's seat; the first contact including: a first common terminal connected to a first end of the passenger's seat motor; a first normally opened terminal connected to a positive electrode of a power supply of the vehicle via a wire, and connected to the first common terminal in response to closing operation for closing the window at the passenger's seat; and a first normally closed terminal; the second contact including: a second common terminal connected to a second end of the passenger's seat motor; a second normally opened terminal connected to the positive electrode of the power supply via the wire, and connected to the second common terminal in response to opening operation for opening the window at the passenger's seat; and a second normally closed terminal; the window opening-closing control apparatus including: a driver's seat main switch operated to open and close the window at the driver's seat; a passenger's seat main switch having a third contact operated to close the window at the passenger's seat and a fourth contact operated to open the window at the passenger's seat, the passenger's seat main switch operated to open and close the window at the passenger's seat; a motor current detector configured to detect current flowing to the passenger's seat motor; a first relay circuit unit including a first common relay terminal connected to the first normally closed terminal, a first normally opened relay terminal connected to the positive electrode of the power supply, and a first normally closed relay terminal connected to ground; a second relay circuit unit including a second common relay terminal connected to the second normally closed terminal, a second normally opened relay terminal connected to the positive electrode of the power supply, and

a second normally closed relay terminal connected to ground; an operation detector configured to detect operation to the passenger's seat sub switch in accordance with motor current detected by the motor current detector;

and an opening-closing controller configured to control the first relay circuit unit and the second relay circuit unit in accordance with the operation to the passenger's seat sub switch; in which the operation detector detects whether the closing operation or the opening operation is performed to the passenger's seat sub switch in accordance with an amount of the motor current and detects duration of the operation to the passenger's seat sub switch, and the opening-closing controller controls the first relay circuit unit or the second relay circuit unit to execute automatic motion of automatically closing or opening the window at the passenger's seat in accordance with the duration of the operation to the passenger's seat sub switch.

The window opening-closing control system according to one or more embodiments of the disclosure detects whether the closing operation for closing the window at the passenger's seat or the opening operation for opening the window at the passenger's seat is performed to the passenger's seat sub switch in accordance with the amount of the motor current, detects the duration of the operation to the passenger's seat sub switch, and controls the first relay circuit unit or the second relay circuit unit to execute the automatic motion of automatically closing or opening the window at the passenger's seat in accordance with the duration of the operation to the passenger's seat sub switch.

The window at the passenger's seat can be thus opened and closed automatically with the operation switch that is provided at the passenger's seat, includes the contact for manual operation, and is not provided with any member for automatic operation.

The operation detector and the opening-closing controller can be each embodied by a CPU or the like.

The operation detector can control the first relay circuit unit or the second relay circuit unit to execute the automatic motion if the duration of the operation to the passenger's seat sub switch is less than a predetermined first prescribed time period.

The window at the passenger's seat can be thus opened and closed automatically by short push operation or the like to the passenger's seat operation switch.

If the operation detector detects that the duration of the closing operation to the passenger's seat sub switch is not less than a predetermined second prescribed time period shorter than the first prescribed time period and less than the first prescribed time period, the opening-closing controller can connect the first common relay terminal and the first normally opened relay terminal for the second prescribed time period and can keep the connection for more than the first prescribed time period, if the operation detector detects that the duration of the closing operation to the passenger's seat sub switch is not less than the first prescribed time period, the opening-closing controller can connect the first common relay terminal and the first normally opened relay terminal for the second prescribed time period and can subsequently switch to connect the first common relay terminal to the first normally closed relay terminal for the first prescribed time period, if the operation detector detects that the duration of the opening operation to the passenger's seat sub switch is not less than a predetermined second prescribed time period shorter than the first prescribed time period and less than the first prescribed time period, the opening-closing controller can connect the second common relay terminal and the second normally opened relay terminal

for the second prescribed time period and can keep the connection for more than the first prescribed time period, and if the operation detector detects that the duration of the opening operation to the passenger's seat sub switch is not less than the first prescribed time period, the opening-closing controller can connect the second common relay terminal and the second normally opened relay terminal for the second prescribed time period and can subsequently switch to connect the second common relay terminal to the second normally closed relay terminal for the first prescribed time period.

The window at the passenger's seat can be thus opened and closed automatically by short push operation or the like to the passenger's seat operation switch, and can be also prevented from opening and closing discontinuously.

The opening-closing controller connects the first common relay terminal and the first normally opened relay terminal if the closing operation to the passenger's seat sub switch ends before the first prescribed time period elapses, and the opening-closing controller connects the second common relay terminal and the second normally opened relay terminal if the opening operation to the passenger's seat sub switch ends before the first prescribed time period elapses.

The window at the passenger's seat can be thus opened and closed automatically by short push operation or the like to the passenger's seat operation switch.

The opening-closing controller can control the first relay circuit unit or the second relay circuit unit to execute the automatic motion if the duration of the operation to the passenger's seat sub switch is more than a predetermined third prescribed time period.

The window at the passenger's seat can be thus opened and closed automatically by long push operation or the like to the passenger's seat operation switch.

The opening-closing controller can connect the first common relay terminal and the first normally opened relay terminal if the closing operation to the passenger's seat sub switch continues for not less than the third prescribed time period and can keep the connection between the first common relay terminal and the first normally opened relay terminal after the closing operation ends, and the opening-closing controller can connect the second common relay terminal and the second normally opened relay terminal if the opening operation to the passenger's seat sub switch continues for not less than the first prescribed time period and can keep the connection between the second common relay terminal and the second normally opened relay terminal after the opening operation ends.

The window at the passenger's seat can be thus opened and closed automatically by long push operation or the like to the passenger's seat operation switch.

The operation detector can detect whether the closing operation or the opening operation is performed to the passenger's seat sub switch in accordance with the amount of the motor current.

An operation direction of the passenger's seat sub switch can be thus detected with no provision of any sensor or the like.

One or more embodiments of the disclosure also provide a window opening-closing control apparatus connected to a passenger's seat unit provided at a passenger's seat other than a driver's seat in a vehicle, the passenger's seat unit including: a momentary passenger's seat sub switch having a first contact operated to close a window at the passenger's seat and a second contact operated to open the window at the passenger's seat; the first contact including: a first common terminal connected to a first end of a passenger's seat motor

configured to open and close the window at the passenger's seat; a first normally opened terminal connected to a positive electrode of a power supply of the vehicle via a wire, and connected to the first common terminal in response to closing operation for closing the window at the passenger's seat; and a first normally closed terminal; the second contact including: a second common terminal connected to a second end of the passenger's seat motor; a second normally opened terminal connected to the positive electrode of the power supply via the wire, and connected to the second common terminal in response to opening operation for opening the window at the passenger's seat; and a second normally closed terminal; the window opening-closing control apparatus provided at the driver's seat in the vehicle and configured to control a driver's seat motor configured to open and close a window at the driver's seat and the passenger's seat motor; the window opening-closing control apparatus including: a driver's seat main switch operated to open and close the window at the driver's seat; a passenger's seat main switch having a third contact operated to close the window at the passenger's seat and a fourth contact operated to open the window at the passenger's seat, the passenger's seat main switch operated to open and close the window at the passenger's seat; a motor current detector configured to detect current flowing to the passenger's seat motor; a first relay circuit unit including a first common relay terminal connected to the first normally closed terminal, a first normally opened relay terminal connected to the positive electrode of the power supply, and a first normally closed relay terminal connected to ground; a second relay circuit unit including a second common relay terminal connected to the second normally closed terminal, a second normally opened relay terminal connected to the positive electrode of the power supply, and a second normally closed relay terminal connected to ground; an operation detector configured to detect operation to the passenger's seat sub switch in accordance with motor current detected by the motor current detector; and an opening-closing controller configured to control the first relay circuit unit and the second relay circuit unit in accordance with the operation to the passenger's seat sub switch; in which the operation detector detects whether the closing operation or the opening operation is performed to the passenger's seat sub switch in accordance with an amount of the motor current and detects duration of the operation to the passenger's seat sub switch, and the opening-closing controller controls the first relay circuit unit or the second relay circuit unit to execute automatic motion of automatically closing or opening the window at the passenger's seat in accordance with the duration of the operation to the passenger's seat sub switch.

The window opening-closing control apparatus according to one or more embodiments of the disclosure detects whether the closing operation for closing the window at the passenger's seat or the opening operation for opening the window at the passenger's seat is performed to the passenger's seat sub switch in accordance with the amount of the motor current, detects the duration of the operation to the passenger's seat sub switch, and controls the first relay circuit unit or the second relay circuit unit to execute the automatic motion of automatically closing or opening the window at the passenger's seat in accordance with the duration of the operation to the passenger's seat sub switch.

The window at the passenger's seat can be thus opened and closed automatically with the operation switch that is provided at the passenger's seat, includes the contact for manual operation, and is not provided with any member for automatic operation.

The operation detector and the opening-closing controller can be each embodied by a CPU or the like.

According to the one or more embodiments of the disclosure, the window at the passenger's seat can be opened and closed automatically with the operation switch that is provided at the passenger's seat, includes the contact for manual operation, and is not provided with any member for automatic operation.

10 BRIEF DESCRIPTION OF THE DRAWINGS

FIG. 1 is a circuit diagram of an automatic window system according to one or more embodiments of the disclosure;

15 FIG. 2 is a block diagram depicting exemplary functional configurations in a controller;

FIG. 3 is a diagram depicting a state of the automatic window system when manually closing operation is performed to a driver's seat main switch;

20 FIG. 4 is a diagram depicting a state of the automatic window system when manually opening operation is performed to a driver's seat main switch;

FIG. 5 is a diagram depicting a state of the automatic window system when the manually closing operation is performed to a passenger's seat main switch;

25 FIG. 6 is a diagram depicting a state of the automatic window system when the manually opening operation is performed to the passenger's seat main switch;

FIG. 7 is a diagram depicting a state of the automatic window system when closing operation is performed to a passenger's seat sub switch;

30 FIG. 8 is a diagram depicting a state of the automatic window system when opening operation is performed to the passenger's seat sub switch;

FIG. 9 is an explanatory diagram on a method of detecting a position of each vehicle window in an opening-closing direction;

35 FIG. 10 is an explanatory diagram on a method of detecting interposition at each vehicle window;

FIG. 11 is an explanatory flowchart of a window opening-closing process by a passenger's seat sub switch according to a first embodiment;

40 FIG. 12 is an explanatory timing chart of the window opening-closing process by the passenger's seat sub switch according to the first embodiment;

FIG. 13 is an explanatory timing chart of the window opening-closing process by the passenger's seat sub switch according to the first embodiment;

45 FIG. 14 is an explanatory diagram of automatically closing motion with the passenger's seat sub switch according to the first embodiment;

FIG. 15 is an explanatory diagram of the automatically closing motion with the passenger's seat sub switch according to the first embodiment;

50 FIG. 16 is an explanatory diagram of the automatically closing motion with the passenger's seat sub switch according to the first embodiment;

FIG. 17 is an explanatory diagram of automatically opening motion with the passenger's seat sub switch according to the first embodiment;

55 FIG. 18 is an explanatory diagram of the automatically opening motion with the passenger's seat sub switch according to the first embodiment;

FIG. 19 is an explanatory diagram of the automatically opening motion with the passenger's seat sub switch according to the first embodiment;

FIG. 20 is an explanatory flowchart of a window opening-closing process by a passenger's seat sub switch according to a second embodiment;

FIG. 21 is an explanatory timing chart of the window opening-closing process by the passenger's seat sub switch according to the second embodiment;

FIG. 22 is an explanatory timing chart of the window opening-closing process by the passenger's seat sub switch according to the second embodiment;

FIG. 23 is an explanatory diagram of automatically closing motion with the passenger's seat sub switch according to the second embodiment;

FIG. 24 is an explanatory diagram of automatically opening motion with the passenger's seat sub switch according to the second embodiment;

FIG. 25 is an explanatory flowchart of a window opening-closing process by a passenger's seat sub switch according to a third embodiment;

FIG. 26 is an explanatory timing chart of the window opening-closing process by the passenger's seat sub switch according to the third embodiment;

FIG. 27 is an explanatory timing chart of the window opening-closing process by the passenger's seat sub switch according to the third embodiment;

FIG. 28 is an explanatory diagram of automatically closing motion with the passenger's seat sub switch according to the third embodiment;

FIG. 29 is an explanatory diagram of the automatically closing motion with the passenger's seat sub switch according to the third embodiment;

FIG. 30 is an explanatory diagram of the automatically closing motion with the passenger's seat sub switch according to the third embodiment;

FIG. 31 is an explanatory diagram of the automatically closing motion with the passenger's seat sub switch according to the third embodiment;

FIG. 32 is an explanatory diagram of automatically opening motion with the passenger's seat sub switch according to the third embodiment;

FIG. 33 is an explanatory diagram of the automatically opening motion with the passenger's seat sub switch according to the third embodiment;

FIG. 34 is an explanatory diagram of the automatically opening motion with the passenger's seat sub switch according to the third embodiment; and

FIG. 35 is an explanatory diagram of the automatically opening motion with the passenger's seat sub switch according to the third embodiment.

DETAILED DESCRIPTION

Embodiments of the disclosure (hereinafter, referred to as embodiments) will now be described below. In embodiments of the disclosure, numerous specific details are set forth in order to provide a more thorough understanding of the invention. However, it will be apparent to one of ordinary skill in the art that the invention may be practiced without these specific details. In other instances, well-known features have not been described in detail to avoid obscuring the invention. Description will be made in the following order.

1. Embodiments
2. Modification examples
- <1. Embodiments>

{Exemplary Configuration of Automatic Window System 1}

FIG. 1 is a circuit diagram depicting an exemplary configuration of the automatic window system 1, as an automatic window system according to one or more embodiments.

ments of the disclosure. The following description relates to a case where the automatic window system 1 opens and closes four vehicle windows at a driver's seat, a front passenger's seat, a rear right passenger's seat, and a rear left passenger's seat.

The window at the driver's seat, the window at the front passenger's seat, the window at the rear right passenger's seat, and the window at the rear left passenger's seat will be also simply referred to as the driver's seat window, the front passenger's seat window, the rear right passenger's seat window, and the rear left passenger's seat window, respectively. Each of the seats other than the driver's seat will be generically referred to as a passenger's seat.

The automatic window system 1 includes a window opening-closing control system 11, a motor 12, motors 13a to 13c, a main relay 14, a body control module (BCM) 15, an ignition switch 16, and a power supply B.

The window opening-closing control system 11 includes an operation unit configured to open and close a vehicle window. The window opening-closing control system 11 controls turning ON/OFF and a direction of motor current flowing to the motors 12 and 13a to 13c in accordance with operation to the operation unit, so as to control opening and closing each vehicle window. The motor 12 is configured to open and close the driver's seat window, whereas the motors 13a to 13c are configured to open and close the front passenger's seat window, the rear right passenger's seat window, and the rear left passenger's seat window, respectively.

The main relay 14 opens and closes an electric circuit from the power supply B to each of the motors 13a to 13c under the control of the BCM 15. Specifically, the BCM 15 turns ON a contact of the main relay 14 if the ignition switch 16 is turned ON. Motor current can be supplied from the power supply B to each of the motors 13a to 13c in this case, to open and close the front passenger's seat window and the rear right and rear left passenger's seat windows. In contrast, the BCM 15 turns OFF the contact of the main relay 14 if the ignition switch 16 is turned OFF. Motor current cannot be supplied from the power supply B to each of the motors 13a to 13c in this case, so as not to open and close the front passenger's seat window and the rear right and rear left passenger's seat windows.

The power supply B can be configured as a battery provided to the vehicle, and supplies driving power for each unit in the automatic window system 1.

The window opening-closing control system 11 includes a window opening-closing control apparatus 21, and passenger's seat units 22a to 22c. The passenger's seat units 22a to 22c are connected to a positive electrode of the power supply B via the main relay 14.

The window opening-closing control apparatus 21 is disposed near the driver's seat (e.g. inside a door at the driver's seat), and is configured to open and close, at the driver's seat, the driver's seat window and the passenger's seat windows. The window opening-closing control apparatus 21 can be configured as a single unit including a single case and respective components accommodated therein.

The passenger's seat unit 22a is disposed near the front passenger's seat (e.g. inside a door at the front passenger's seat), and is configured to open and close the front passenger's seat window at the front passenger's seat.

The passenger's seat unit 22b is disposed near the rear right passenger's seat (e.g. inside a door at the rear right passenger's seat), and is configured to open and close the rear right passenger's seat window at the rear right passenger's seat.

The passenger's seat unit 22c is disposed near the rear left passenger's seat (e.g. inside a door at the rear left passenger's seat), and is configured to open and close the rear left passenger's seat window at the rear left passenger's seat.

The window opening-closing control apparatus 21 includes a controller 31, a driver's seat main switch 32, passenger's seat main switches 33a to 33c, a driver's seat control circuit 34, passenger's seat control circuits 35a to 35c, and a power supply circuit 36.

The controller 31 can be configured as a central processing unit (CPU). The controller 31 controls the driver's seat control circuit 34 and the passenger's seat control circuits 35a to 35c in accordance with operation to the driver's seat main switch 32 and the passenger's seat main switches 33a to 33c, so as to control opening and closing the vehicle windows. The controller 31 also detects a motion direction of each window (whether it is opening or closing), a position of each window in an opening-closing direction (hereinafter, simply referred to as a position of each window), and interposition, in accordance with detection results and the like of motor current supplied from the driver's seat control circuit 34 and the passenger's seat control circuits 35a to 35c. Interposition herein indicates a phenomenon that an object is interposed between a closing window and a vehicle body.

The driver's seat main switch 32 is a momentary operation switch configured to open and close the driver's seat window at the driver's seat. The driver's seat main switch 32 includes contacts 51L, 51U, 51D, and 51A, as well as an input circuit 52.

The contact 51L is of a normally opened type and is operated to set a locking function of invalidating operation to passenger's seat sub switches 91a to 91c in the passenger's seat units 22a to 22c. The contact 51L is turned ON if operation for setting the locking function is performed, and is turned OFF if operation for canceling the locking function is performed.

The contact 51U is of the normally opened type and is operated to close the driver's seat window. The contact 51U is turned ON if closing operation for closing the driver's seat window is performed to the driver's seat main switch 32, and is turned OFF if the closing operation is not performed.

The contact 51D is of the normally opened type and is operated to open the driver's seat window. The contact 51D is turned ON if opening operation for opening the driver's seat window is performed to the driver's seat main switch 32, and is turned OFF if the opening operation is not performed.

The contact 51A is of the normally opened type and is operated to automatically open and close the driver's seat window. The contact 51A is turned ON if closing operation for automatically closing the driver's seat window (hereinafter, referred to as automatically closing operation) or opening operation for automatically opening the driver's seat window (hereinafter, referred to as automatically opening operation) is performed to the driver's seat main switch 32.

Closing operation for manually closing a window will be also referred to as manually closing operation in comparison to the automatically closing operation, whereas opening operation for manually opening a window will be also referred to as manually opening operation.

The manual operation and the automatic operation to the driver's seat main switch 32 are performed in different manners according to specifications of the switch. For example, the manual operation and the automatic operation are distinguished from each other depending on stress of the

operation to an operation knob (not depicted) of the driver's seat main switch 32. The manually closing operation can be performed by lightly pulling upward the operation knob, and the automatically closing operation can be performed by applying more force to further heavily pull upward the operation knob. In contrast, the manually opening operation can be performed by lightly pushing the operation knob, and the automatically opening operation can be performed by applying more force to further heavily push downward the operation knob.

Alternatively, the manual operation and the automatic operation are distinguished from each other depending on operation time periods to the operation knob of the driver's seat main switch. The manually closing operation can be performed by pulling upward the operation knob for less than a predetermined time period, and the automatically closing operation can be performed by pulling upward the operation knob for not less than the predetermined time period. In contrast, the manually opening operation can be performed by pushing the operation knob for less than the predetermined time period, and the automatically opening operation can be performed by pushing the operation knob for not less than the predetermined time period.

The input circuit 52 transmits, to the controller 31, signals indicating states of the contacts 51L, 51U, 51D, and 51A.

The passenger's seat main switch 33a is a momentary operation switch configured to open and close the front passenger's seat window at the driver's seat. The passenger's seat main switch 33a includes contacts 61Ua, 61Da, and 61Aa, as well as an input circuit 62a.

The contact 61Ua is of the normally opened type and is operated to close the front passenger's seat window. The contact 61Ua is turned ON if the closing operation for closing the front passenger's seat window is performed to the passenger's seat main switch 33a, and is turned OFF if the closing operation is not performed.

The contact 61Da is of the normally opened type and is operated to open the front passenger's seat window. The contact 61Da is turned ON if the opening operation for opening the front passenger's seat window is performed to the passenger's seat main switch 33a, and is turned OFF if the opening operation is not performed.

The contact 61Aa is of the normally opened type and is operated to automatically open and close the front passenger's seat window. The contact 61Aa is turned ON if the automatically closing operation or the automatically opening operation is performed to the passenger's seat main switch 33a.

The manual operation and the automatic operation to the passenger's seat main switch 33a can be performed in manners similar to the manual operation and the automatic operation to the driver's seat main switch 32.

The input circuit 62a transmits, to the controller 31, signals indicating states of the contacts 61Ua, 61Da, and 61Aa.

The passenger's seat main switch 33b and the passenger's seat main switch 33c are momentary operation switches configured to open and close, at the driver's seat, the rear right passenger's seat and the rear left passenger's seat, respectively. The passenger's seat main switch 33b and the passenger's seat main switch 33c each have a circuit configuration similar to that of the passenger's seat main switch 33a and will not be described or depicted repeatedly. The passenger's seat main switch 33b not depicted includes sections denoted by reference signs that are obtained by replacing the last letter "a" in the reference signs of the sections in the passenger's seat main switch 33a with the

11

letter "b". The passenger's seat main switch **33c** not depicted includes sections denoted by reference signs that are obtained by replacing the last letter "a" in the reference signs of the sections in the passenger's seat main switch **33a** with the letter "c".

The driver's seat control circuit **34** controls the motor **12**. The driver's seat control circuit **34** includes a switching circuit **71**, a driving circuit **72**, an amplifier circuit **73**, and a resistor **R11**.

The switching circuit **71** includes a relay circuit **71U** configured to be driven to close the driver's seat window (only a relay contact **71YU** is depicted) and a relay circuit **71D** configured to be driven to open the driver's seat window (only a relay contact **71YD** is depicted).

The relay circuit **71U** includes a coil **71XU** (not depicted) and the relay contact **71YU** serving as a transfer contact configured to be transferred in state by driving current flowing through the coil **71XU**. The relay contact **71YU** includes a normally opened terminal (NO terminal) **a** that is connected to the positive electrode of the power supply **B** via a wire **L3**. The relay contact **71YU** includes a normally closed terminal (NC terminal) **b** that is connected to ground via the resistor **R11**. The relay contact **71YU** includes a common terminal **c** that is connected to a first end of the motor **12** via a wire **L1**.

The relay circuit **71D** includes a coil **71XD** (not depicted) and the relay contact **71YD** serving as a transfer contact configured to be transferred in state by driving current flowing through the coil **71XD**. The relay contact **71YD** includes a normally opened terminal (NO terminal) **a** that is connected to the positive electrode of the power supply **B** via the wire **L3**. The relay contact **71YD** includes a normally closed terminal (NC terminal) **b** that is connected to ground via the resistor **R11**. The relay contact **71YD** includes a common terminal **c** that is connected to a second end of the motor **12** via a wire **L2**.

The driving circuit **72** drives the relay circuits **71U** and **71D** under the control of the controller **31**. Specifically, the driving circuit **72** controls driving current to the coil **71XU** of the relay circuit **71U** and the coil **71XD** of the relay circuit **71D** under the control of the controller **31**, so as to control the states of the relay contacts **71YU** and **71YD**.

The amplifier circuit **73** is connected to the both ends of the resistor **R11**. The amplifier circuit **73** amplifies voltage generated at the both ends of the resistor **R11** by motor current at the motor **12** outputted from the switching circuit **71**, and transmits the amplified voltage to the controller **31**. The controller **31** monitors motor current at the motor **12** on the basis of voltage received from the amplifier circuit **73**.

Hereinafter, the direction of motor current flowing through the relay contact **71YU**, the motor **12**, and the relay contact **71YD** in the mentioned order will be called a forward direction whereas the direction of motor current flowing through the relay contact **71YD**, the motor **12**, and the relay contact **71YU** in the mentioned order will be called a backward direction. Also, assume that the driver's seat window shifts upward and closes if motor current flows in the forward direction to the motor **12** and the driver's seat window shifts downward and opens if motor current flows in the backward direction to the motor **12**.

The passenger's seat control circuit **35a** controls the motor **13a** via the passenger's seat unit **22a**. The passenger's seat control circuit **35a** includes a switching circuit **81a**, a driving circuit **82a**, an amplifier circuit **83a**, and a resistor **R21a**.

The switching circuit **81a** includes a relay circuit **81Ua** configured to be driven to close the front passenger's seat

12

window (only a relay contact **81YUa** is depicted) and a relay circuit **81Da** configured to be driven to open the front passenger's seat window (only a relay contact **81YDa** is depicted).

The relay circuit **81Ua** includes a coil **81XUa** (not depicted) and the relay contact **81YUa** serving as a transfer contact configured to be transferred in state by driving current flowing through the coil **81XUa**. The relay contact **81YUa** includes a normally opened terminal (NO terminal) **a** that is connected to the positive electrode of the power supply **B** via a wire **L6** and the main relay **14**. The relay contact **81YUa** includes a normally closed terminal (NC terminal) **b** that is connected to ground via the resistor **R21a**. The relay contact **81YUa** includes a common terminal **c** that is connected to a terminal **b** of a contact **91Ua** in the passenger's seat sub switch **91a** via a wire **L4a**.

The relay circuit **81Da** includes a coil **81XDa** (not depicted) and the relay contact **81YDa** serving as a transfer contact configured to be transferred in state by driving current flowing through the coil **81XDa**. The relay contact **81YDa** includes a normally opened terminal (NO terminal) **a** that is connected to the positive electrode of the power supply **B** via the wire **L6** and the main relay **14**. The relay contact **81YDa** includes a normally closed terminal (NC terminal) **b** that is connected to ground via the resistor **R21a**. The relay contact **81YDa** includes a common terminal **c** that is connected to a terminal **b** of a contact **91Da** in the passenger's seat sub switch **91a** via a wire **L5a**.

The driving circuit **82a** drives the relay circuits **81Ua** and **81Da** under the control of the controller **31**. Specifically, the driving circuit **82a** controls driving current to the coil **81XUa** of the relay circuit **81Ua** and the coil **81XDa** of the relay circuit **81Da** under the control of the controller **31**, so as to control the states of the relay contacts **81YUa** and **81YDa**.

The amplifier circuit **83a** is connected to the both ends of the resistor **R21a** serving as a motor current detector configured to detect motor current flowing to the motor **13a**. The amplifier circuit **83a** amplifies voltage generated at the both ends of the resistor **R21a** by motor current at the motor **13a** outputted from the switching circuit **71**, and transmits the amplified voltage to the controller **31**. The controller **31** monitors motor current at the motor **13a** on the basis of voltage received from the amplifier circuit **83a**.

The passenger's seat control circuit **35b** controls the motor **13b** via the passenger's seat unit **22b**, whereas the passenger's seat control circuit **35c** controls the motor **13c** via the passenger's seat unit **22c**. The passenger's seat control circuit **35b** and the passenger's seat control circuit **35c** each have a circuit configuration similar to that of the passenger's seat control circuit **35a** and will not be described or depicted repeatedly. The passenger's seat control circuit **35b** not depicted includes sections denoted by reference signs that are obtained by replacing the last letter "a" in the reference signs of the sections in the passenger's seat control circuit **35a** with the letter "b". The passenger's seat control circuit **35c** not depicted includes sections denoted by reference signs that are obtained by replacing the last letter "a" in the reference signs of the sections in the passenger's seat control circuit **35a** with the letter "c".

The power supply circuit **36** is connected to the positive electrode of the power supply **B** via the wire **L3** to supply each section in the window opening-closing control apparatus **21** with power from the power supply **B**.

The passenger's seat unit **22a** includes the passenger's seat sub switch **91a**.

The passenger's seat sub switch **91a** is a momentary operation switch configured to open and close the front passenger's seat window at the front passenger's seat window. The passenger's seat sub switch **91a** includes the contacts **91Ua** and **91Da**.

The contact **91Ua** serves as a transfer contact configured to be transferred if the passenger's seat sub switch **91a** is operated to close the front passenger's seat window. The contact **91Ua** includes a normally opened terminal (NO terminal) a that is connected to the positive electrode of the power supply B via a wire **L6** and the main relay **14**. The contact **91Ua** includes a normally closed terminal (NC terminal) b that is connected to the terminal c of the relay contact **81YUa** via the wire **L4a**. The contact **91Ua** includes a common terminal c that is connected to a first end of the motor **13a** via a wire **L7a**. The terminal a and the terminal c are connected to each other if the closing operation for closing the front passenger's seat window is performed to the passenger's seat sub switch **91a**, and the terminal b and the terminal c are connected to each other if the closing operation is not performed.

The contact **91Da** serves as a transfer contact configured to be transferred if the passenger's seat sub switch **91a** is operated to open the front passenger's seat window. The contact **91Da** includes a normally opened terminal (NO terminal) a that is connected to the positive electrode of the power supply B via the wire **L6** and the main relay **14**. The contact **91Da** includes a normally closed terminal (NC terminal) b that is connected to the terminal c of the relay contact **81YDa** via the wire **L5a**. The contact **91Da** includes a common terminal c that is connected to a second end of the motor **13a** via a wire **L8a**. The terminal a and the terminal c are connected to each other if the opening operation for opening the front passenger's seat window is performed to the passenger's seat sub switch **91a**, and the terminal b and the terminal c are connected to each other if the opening operation is not performed.

Hereinafter, the direction of motor current flowing through the contact **91Ua**, the motor **13a**, and the contact **91Da** in the mentioned order will be called a forward direction whereas the direction of motor current flowing through the contact **91Da**, the motor **13a**, and the contact **91Ua** in the mentioned order will be called a backward direction. Also, assume that the front passenger's seat window shifts upward and closes if motor current flows in the forward direction to the motor **13a** and the front passenger's seat window shifts downward and opens if motor current flows in the backward direction to the motor **13a**.

The passenger's seat units **22b** and **22c** each have a circuit configuration similar to that of the passenger's seat unit **22a** and will not be described repeatedly.

The window opening-closing control apparatus **21** and the motor **12** are connected via the two wires **L1** and **L2**. The window opening-closing control apparatus **21** and the passenger's seat units **22a** to **22c** are connected via six wires **L4a** to **L4c** and **L5a** to **L5c**. The window opening-closing control apparatus **21** can be thus easily connected to the motor **12** and the passenger's seat units **22a** to **22c** in the vehicle via such a small number of wires.

As depicted in FIG. 1, the window opening-closing control apparatus **21** and the passenger's seat units **22a** to **22c** are connected via the wire **L6**, which connects the main relay **14**, the window opening-closing control apparatus **21**, and the passenger's seat units **22a** to **22c**. Accordingly, the window opening-closing control apparatus **21** and the passenger's seat units **22a** to **22c** are not necessarily connected directly via the wire **L6**.

Hereinafter, the motors **13a** to **13c** will be each simply referred to as the motor **13** if there is no need to distinguish the motors **13a** to **13c** from one another. Furthermore, the passenger's seat units **22a** to **22c**, the passenger's seat main switches **33a** to **33c**, and the passenger's seat control circuits **35a** to **35c** will be each simply referred to as the passenger's seat unit **22**, the passenger's seat main switch **33**, and the passenger's seat control circuit **35**, respectively, if there is no need to distinguish the passenger's seat units **22a** to **22c**, the passenger's seat main switches **33a** to **33c**, and the passenger's seat control circuits **35a** to **35c** from one another.

Moreover, if there is no need to distinguish the sections in the passenger's seat units **22a** to **22c**, the passenger's seat main switches **33a** to **33c**, and the passenger's seat control circuits **35a** to **35c** from one another, respectively, these sections will be denoted by reference signs that are obtained by removing the last letters "a" to "c". For example, the passenger's seat sub switches **91a** to **91c** in the passenger's seat units **22a** to **22c** will be each simply referred to as the passenger's seat sub switch **91** if there is no need to distinguish the passenger's seat sub switches **91a** to **91c** from one another.

Connecting the terminal a and the terminal c at a transfer contact (turning ON an a contact) will be hereinafter referred to as turning ON the transfer contact. For example, connecting the terminal a and the terminal c at the contact **91Ua** will be hereinafter referred to as turning ON the contact **91Ua**. Similarly, connecting the terminal b and the terminal c at a transfer contact (turning ON a b contact) will be hereinafter referred to as turning OFF the transfer contact. For example, connecting the terminal b and the terminal c at the contact **91Ua** will be hereinafter referred to as turning OFF the contact **91Ua**.

{Exemplary Functional Configurations in Controller 31}

FIG. 2 depicts exemplary functional configurations in the controller **31**. The controller **31** includes an operation detector **101**, a window position detector **102**, an interposition detector **103**, and an opening-closing controller **104**. FIG. 2 depicts only part of the functional configurations in the controller **31**, which will be described hereinafter.

The operation detector **101** detects operation to the driver's seat main switch **32** and the passenger's seat main switches **33a** to **33c** in accordance with signals transmitted from the input circuits **52** and **62a** to **62c**. The operation detector **101** monitors motor current at the motors **13a** to **13c** on the basis of voltage received from the amplifier circuits **83a** to **83c**, respectively. The operation detector **101** detects operation to the passenger's seat sub switches **91a** to **91c** in accordance with motor current at the motors **13a** to **13c**, respectively. The operation detector **101** transmits the detection results to the respective sections in the controller **31**.

The window position detector **102** monitors motor current at the motors **12** and **13a** to **13c** on the basis of voltage received from the amplifier circuits **73** and **83a** to **83c**, respectively. The window position detector **102** detects positions and motion directions of the respective vehicle seat windows in accordance with the motor current at the motors **12** and **13a** to **13c** as well as the detection results on the operation to the driver's seat main switch **32** and the passenger's seat main switches **33a** to **33c**. The window position detector **102** transmits the detection results to the respective sections in the controller **31**.

The interposition detector **103** monitors motor current at the motors **12** and **13a** to **13c** on the basis of voltage received from the amplifier circuits **73** and **83a** to **83c**, respectively. The interposition detector **103** detects interposition at the respective windows in accordance with the motor current at

the motors 12 and 13a to 13c, the detection results on the operation to the driver's seat main switch 32 and the passenger's seat main switches 33a to 33c, and the detection results on the positions and the motion directions of the respective vehicle seat windows. The interposition detector 103 transmits the detection results to the respective sections in the controller 31.

The opening-closing controller 104 controls opening and closing the respective vehicle windows in accordance with the operation to the driver's seat main switch 32, the passenger's seat main switches 33a to 33c, and the passenger's seat sub switches 91a to 91c, as well as the detection results on the positions and the motion directions of the respective windows and the interposition at the respective windows. Specifically, the opening-closing controller 104 controls the driving circuit 72 and the relay circuits 71U and 71D, so as to control motor current at the motor 12 and opening and closing the driver's seat window. The opening-closing controller 104 also controls the driving circuits 82a to 82c and the relay circuits 81Ua to 81Uc and 81Da to 81Dc, so as to control motor current at the motors 13a to 13c and opening and closing the front passenger's seat, the rear right passenger's seat, and the rear left passenger's seat.

{Basic Motion of Automatic Window System 1}

Basic motion of the automatic window system 1 will be described next with reference to FIGS. 3 to 8. FIGS. 3 to 8 do not include sections and reference signs not particularly needed in the description.

{When Closing Operation is Performed to Driver's Seat Main Switch 32}

FIG. 3 depicts a state of the automatic window system 1 when the manually closing operation is performed to the driver's seat main switch 32.

If manually closing operation is performed to the driver's seat main switch 32, the contact 51U is turned ON. If the operation detector 101 detects that the contact 51U is ON, the opening-closing controller 104 turns ON the relay contact 71YU via the driving circuit 72. In this case, current flows from the power supply B to ground via the terminal a of the relay contact 71YU, the motor 12, the terminal b of the relay contact 71YD, and the resistor R11. This causes motor current to flow in the forward direction to the motor 12, so as to close the driver's seat window.

If the manually closing operation to the driver's seat main switch 32 is stopped, the contact 51U is turned OFF. If the operation detector 101 detects that the contact 51U is OFF, the opening-closing controller 104 turns OFF the relay contact 71YU via the driving circuit 72. This stops supply of motor current to the motor 12 so as to stop the closing motion of the driver's seat window.

If the automatically closing operation is performed to the driver's seat main switch 32, the contacts 51U and 51A are turned ON. Similarly to the case where the manually closing operation is performed, the relay contact 71YU is turned ON and motor current flows in the forward direction to the motor 12, so as to close the driver's seat window.

Even when the automatically closing operation to the driver's seat main switch 32 is subsequently stopped and the contacts 51U and 51A are turned OFF, the opening-closing controller 104 keeps the state where the relay contact 71YU is ON via the driving circuit 72 until the driver's seat window is fully closed. The driver's seat window is thus automatically fully closed.

If the manually opening operation or the automatically opening operation is performed to the driver's seat main switch 32 while the driver's seat window is automatically closing and the operation detector 101 detects that the

contact 51D is ON, the opening-closing controller 104 turns OFF the relay contact 71YU via the driving circuit 72. This stops the automatically closing motion of the driver's seat window.

{When Opening Operation is Performed to Driver's Seat Main Switch 32}

FIG. 4 depicts a state of the automatic window system 1 when the manually opening operation is performed to the driver's seat main switch 32.

If the manually opening operation is performed to the driver's seat main switch 32, the contact 51D is turned ON. If the operation detector 101 detects that the contact 51D is ON, the opening-closing controller 104 turns ON the relay contact 71YD via the driving circuit 72. In this case, current flows from the power supply B to ground via the terminal a of the relay contact 71YD, the motor 12, the terminal b of the relay contact 71YU, and the resistor R11. This causes motor current to flow in the backward direction to the motor 12, so as to open the driver's seat window.

If the manually opening operation to the driver's seat main switch 32 is stopped, the contact 51D is turned OFF. If the operation detector 101 detects that the contact 51D is OFF, the opening-closing controller 104 turns OFF the relay contact 71YD via the driving circuit 72. This stops supply of motor current to the motor 12 so as to stop the opening motion of the driver's seat window.

If the automatically opening operation is performed to the driver's seat main switch 32, the contacts 51D and 51A are turned ON. Similarly to the case where the manually opening operation is performed, the relay contact 71YD is turned ON and motor current flows in the backward direction to the motor 12, so as to open the driver's seat window. Even when the automatically opening operation to the driver's seat main switch 32 is subsequently stopped and the contacts 51D and 51A are turned OFF, the opening-closing controller 104 keeps the state where the relay contact 71YD is ON via the driving circuit 72 until the driver's seat window is fully opened. The driver's seat window is thus automatically fully opened.

If the manually closing operation or the automatically closing operation is performed to the driver's seat main switch 32 while the driver's seat window is automatically opening and the operation detector 101 detects that the contact 51U is ON, the opening-closing controller 104 turns OFF the relay contact 71YD via the driving circuit 72. This stops the automatically opening motion of the driver's seat window.

{When Closing Operation is Performed to Passenger's Seat Main Switch 33a}

FIG. 5 depicts a state of the automatic window system 1 when the manually closing operation is performed to the passenger's seat main switch 33a.

If the manually closing operation is performed to the passenger's seat main switch 33a, the contact 61Ua is turned ON. If the operation detector 101 detects that the contact 61Ua is ON, the opening-closing controller 104 turns ON the relay contact 81YUa via the driving circuit 82a. In this case, current flows from the power supply B to ground via the main relay 14, the terminal a of the relay contact 81YUa, the terminal b of the contact 91Ua, the motor 13a, the terminal b of the contact 91Da, the terminal b of the relay contact 81YDa, and the resistor R21a. This causes motor current to flow in the forward direction to the motor 13a, so as to close the front passenger's seat window.

If the manually closing operation to the passenger's seat main switch 33a is stopped, the contact 61Ua is turned OFF. If the operation detector 101 detects that the contact 61Ua is

OFF, the opening-closing controller 104 turns OFF the relay contact 81YUa via the driving circuit 82a. This stops supply of motor current to the motor 13a so as to stop the closing motion of the front passenger's seat window.

If the automatically closing operation is performed to the passenger's seat main switch 33a, the contacts 61Ua and 61Aa are turned ON. Similarly to the case where the manually closing operation is performed, the relay contact 81YUa is turned ON and motor current flows in the forward direction to the motor 13a, so as to close the front passenger's seat window. Even when the automatically closing operation to the passenger's seat main switch 33a is subsequently stopped and the contacts 61Ua and 61Aa are turned OFF, the opening-closing controller 104 keeps the state where the relay contact 81YUa is ON via the driving circuit 82a until the front passenger's seat window is fully closed. The front passenger's seat window is thus automatically fully closed.

If the manually opening operation or the automatically opening operation is performed to the passenger's seat main switch 33a while the front passenger's seat window is automatically closing and the operation detector 101 detects that the contact 61Da is ON, the opening-closing controller 104 turns OFF the relay contact 81YUa via the driving circuit 82a. This stops the automatically closing motion of the front passenger's seat.

{When Opening Operation is Performed to Passenger's Seat Main Switch 33a}

FIG. 6 depicts a state of the automatic window system 1 when the manually opening operation is performed to the passenger's seat main switch 33a.

If the manually opening operation is performed to the passenger's seat main switch 33a, the contact 61Da is turned ON. If the operation detector 101 detects that the contact 61Da is ON, the opening-closing controller 104 turns ON the relay contact 81YDa via the driving circuit 82a. In this case, current flows from the power supply B to ground via the main relay 14, the terminal a of the relay contact 81YDa, the terminal b of the contact 91Da, the motor 13a, the terminal b of the contact 91Ua, the terminal b of the relay contact 81YUa, and the resistor R21a. This causes motor current to flow in the backward direction to the motor 13a, so as to open the front passenger's seat window.

If the manually opening operation to the passenger's seat main switch 33a is stopped, the contact 61Da is turned OFF. If the operation detector 101 detects that the contact 61Da is OFF, the opening-closing controller 104 turns OFF the relay contact 81YDa via the driving circuit 82a. This stops supply of motor current to the motor 13a so as to stop the opening motion of the front passenger's seat window.

If the automatically opening operation is performed to the passenger's seat main switch 33a, the contacts 61Da and 61Aa are turned ON. Similarly to the case where the manually opening operation is performed, the relay contact 81YDa is turned ON and motor current flows in the backward direction to the motor 13a, so as to open the front passenger's seat window. Even when the automatically opening operation to the passenger's seat main switch 33a is subsequently stopped and the contacts 61Da and 61Aa are turned OFF, the opening-closing controller 104 keeps the state where the relay contact 81YDa is ON via the driving circuit 82a until the front passenger's seat window is fully opened. The front passenger's seat window is thus automatically fully opened.

If the manually closing operation or the automatically closing operation is performed to the passenger's seat main switch 33a while the front passenger's seat window is

automatically opening and the operation detector 101 detects that the contact 61Ua is ON, the opening-closing controller 104 turns OFF the relay contact 81YDa via the driving circuit 82a. This stops the automatically opening motion of the front passenger's seat.

Although description will not be made in detail, the rear right or rear left passenger's seat window can be opened or closed in similar manners when the passenger's seat main switch 33b or 33c is operated.

10 {When Closing Operation is Performed to Passenger's Seat Sub Switch 91a}

FIG. 7 depicts a state of the automatic window system 1 when the closing operation is performed to the passenger's seat sub switch 91a.

15 If the closing operation is performed to the passenger's seat sub switch 91a, the contact 91Ua is turned ON.

In this case, current flows from the power supply B to ground via the main relay 14, the terminal a of the contact 91Ua, the motor 13a, the terminal b of the contact 91Da, the terminal b of the relay contact 81YDa, and the resistor R21a. This causes motor current to flow in the forward direction to the motor 13a, so as to close the front passenger's seat window.

20 If the closing operation to the passenger's seat sub switch 91a is stopped, the contact 91Ua is turned OFF. This stops supply of motor current to the motor 13a so as to stop the closing motion of the front passenger's seat window.

{When Opening Operation is Performed to Passenger's Seat Sub Switch 91a}

25 FIG. 8 depicts a state of the automatic window system 1 when the opening operation is performed to the passenger's seat sub switch 91a.

30 If the opening operation is performed to the passenger's seat sub switch 91a, the contact 91Da is turned ON. In this case, current flows from the power supply B to ground via the main relay 14, the terminal a of the contact 91Da, the motor 13a, the terminal b of the contact 91Ua, the terminal b of the relay contact 81YUa, and the resistor R21a. This causes motor current to flow in the backward direction to the motor 13a, so as to open the front passenger's seat window.

35 If the opening operation to the passenger's seat sub switch 91a is stopped, the contact 91Da is turned OFF. This stops supply of motor current to the motor 13a so as to stop the opening motion of the front passenger's seat window.

40 As described above, when operation is performed to the passenger's seat sub switch 91a, the front passenger's seat window can be opened or closed with no control by the window opening-closing control apparatus 21.

45 Although description will not be made in detail, the rear right or rear left passenger's seat window can be opened or closed in a similar manner when the passenger's seat sub switch 91b or 91c is operated.

{Method of Detecting Position of Each Vehicle Window}

50 A method of detecting a position of each vehicle window

55 will be described next with reference to FIG. 9.

The window position detector 102 always monitors motor current flowing through the motors 12 and 13a to 13c on the basis of voltage received from the amplifier circuits 73 and 83a to 83c, respectively. Motor current flowing through each 60 of the motors has a ripple. In a state where no interposition occurs, the ripple of the motor current has a stable waveform as depicted in the upper area of FIG. 9.

The window position detector 102 converts the ripple of the motor current to a pulse train depicted in the lower area of FIG. 9. The window position detector 102 calculates rotational speed of each of the motors from the pulse train depicted in FIG. 9, and detects positions of the driver's seat

window and the passenger's seat windows in accordance with the calculated motor rotational speed. This configuration requires no sensor for detection of each window position.

The controller 31 does not receive signals indicating states of the contacts 91Ua and 91Da of the passenger's seat sub switch 91a in this case, so that the controller 31 cannot detect the states of the contacts 91Ua and 91Da. The operation detector 101 cannot detect whether the opening operation or the closing operation is performed to the passenger's seat sub switch 91a directly from the states of the contacts 91Ua and 91Da.

The motor 13a receives a larger load for closing the front passenger's seat window rather than for opening the front passenger's seat window by an amount of lifting upward the window. Accordingly, motor current flowing through the motor 13a is larger for closing the window than motor current for opening the window.

In view of this, if the passenger's seat sub switch 91a is operated to open or close the front passenger's seat window, the operation detector 101 detects an operation direction (the closing operation or the opening operation) of the passenger's seat sub switch 91a in accordance with an amount of motor current at the motor 13a. Similarly, the window position detector 102 detects a motion direction (whether closing or opening) of the window in accordance with the amount of the motor current at the motor 13a.

This applies to the case where the passenger's seat sub switch 91b is operated to open and close the rear right passenger's seat window as well as to the case where the passenger's seat sub switch 91c is operated to open and close the rear left passenger's seat.

When any one of the driver's seat main switch 32 and the passenger's seat main switches 33a to 33c is operated to open or close the corresponding window, the controller 31 receives a signal indicating a state of the contact of the switch. The window position detector 102 can thus detect a motion direction of each window not in accordance with an amount of motor current. It is also possible to detect the motion direction of each window in accordance with the amount of motor current when any one of the driver's seat main switch 32 and the passenger's seat main switches 33a to 33c is operated to open or close the corresponding window.

{Method of Detecting Interposition at each Vehicle Window}

An exemplary method of detecting interposition of each window will be described next with reference to FIG. 10.

If interposition occurs, motor current increases in current level and has a ripple in an unstable waveform with longer periods as depicted in the upper area of FIG. 10.

The interposition detector 103 monitors a change in period T of the ripple and determines that interposition has occurred if the period T reaches or exceeds a predetermined level. The interposition detector 103 can alternatively determine that interposition has occurred if a pulse width W, in place of the period T, reaches or exceeds a predetermined level. Interposition can be detected in accordance with a ripple of motor current in these manners.

The interposition detector 103 determines that interposition has not occurred even though the above condition is satisfied, if the interposition detector 103 determines that no interposition can possibly occur from detection results on operation to the driver's seat main switch 32 and the passenger's seat main switches 33a to 33c and detection

results on positions and motion directions of the respective seat windows. For example, interposition cannot occur when a window is open.

As described above, the window opening-closing control apparatus 21 simply configured with no controllers provided at the passenger's seats other than the driver's seat and fewer wires can control (automatically opening and closing motion as well as manually opening and closing operation) the driver's seat window and the passenger's seat windows at 10 the driver's seat. Furthermore, functions can be improved easily by connecting the window opening-closing control apparatus 21 without modifying the passenger's seat units 22. The window opening-closing control apparatus 21 can be thus easily provided as an additional part or an optional 15 unit. The controller 31 in the window opening-closing control apparatus 21 monitors motor current at the motors 12 and 13a to 13c for the respective seats. The controller 31 can thus detect a position of and interposition at each seat window with no provision of any sensor or the like.

{Achievement Method for Automatic Operation to Passenger's Seat Window With Passenger's Seat Sub Switch 91}

As described above, the passenger's seat sub switch 91 is provided with no contact for automatic operation unlike the driver's seat main switch 32 and the passenger's seat main 25 switch 33. Described below is an achievement method for automatic operation to each passenger's seat window not with a contact for automatic operation but with the passenger's seat sub switch 91.

{First Achievement Method}

30 The first achievement method for the automatic operation to the passenger's seat window with the passenger's seat sub switch 91 will be initially described with reference to FIGS. 11 to 19. According to the first achievement method, the passenger's seat sub switch 91 is operated continuously for 35 not less than a prescribed time period Ta (hereinafter, referred to as long push operation) to achieve the automatic operation. The prescribed time period Ta can be set such that a user can recognize as having operated the passenger's seat sub switch 91 intentionally for a long period of time.

40 A window opening-closing process executed by the automatic window system 1 with the passenger's seat sub switch 91 according to a first embodiment will now be described with reference to the flowchart in FIG. 11 and the timing charts in FIGS. 12 and 13. This window opening-closing 45 process starts when the closing operation or the opening operation is performed to any one of the passenger's seat sub switches 91a to 91c and the operation detector 101 detects that the operation is performed.

FIGS. 12 and 13 each indicate detection values of motor 50 current at the passenger's seat sub switch 91 and the motor 13, as well as chronological state changes at the passenger's seat relay contact on a close side (the contact 81YU) and the passenger's seat relay contact on an open side (the contact 81YD). A timing chart for the automatically closing operation 55 is indicated in the left half divided by the dotted lines in FIG. 12, whereas a timing chart for the automatically opening operation is indicated in the right half divided by the dotted lines in FIG. 12. A timing chart for the manually closing operation is indicated in the left half divided by the dotted lines in FIG. 13, whereas a timing chart for the manually opening operation is indicated in the right half divided by the dotted lines in FIG. 13.

Exemplified below is a case of opening and closing the front passenger's seat window with the passenger's seat sub 60 switch 91a. The passenger's seat in the flowchart in FIG. 11 and the timing charts in FIGS. 12 and 13 mainly refer to the front passenger's seat in the following description.

21

In step S1, the operation detector 101 determines whether or not the closing operation is performed. If the closing operation or the opening operation is performed to the passenger's seat sub switch 91a and the contact 91Ua or 91Da is turned ON, inrush current flows when the motor 13a starts and then motor current comes into a stable state, as indicated in FIGS. 12 and 13. As described above, motor current flowing to the motor 13a is larger for closing the front passenger's seat window than motor current for opening the front passenger's seat window in the stable state.

For example, the operation detector 101 detects motor current at the motor 13a in accordance with voltage received from the amplifier circuit 83a, and compares the detection value with a predetermined threshold Ia. This threshold Ia can be set between the maximum value of the motor current flowing to the motor 13a for opening the front passenger's seat window and the minimum value of the motor current flowing to the motor 13a for closing the front passenger's seat window in the stable state. If the detection value of the motor current is not less than the threshold Ia, the operation detector 101 determines that the closing operation is performed. The process flow then proceeds to step S2.

The automatic window system 1 comes into the state depicted in FIG. 7 in this case, and motor current flows in the forward direction to the motor 13a so as to start closing motion of the front passenger's seat window.

In step S2, the operation detector 101 determines whether or not the closing operation is performed continuously. For example, if the detection value of the motor current at the motor 13a is not less than the threshold Ia, the operation detector 101 determines that the closing operation is performed continuously. The process flow then proceeds to step S3.

In step S3, the operation detector 101 determines whether or not the prescribed time period Ta has elapsed. If the operation detector 101 determines that the prescribed time period Ta has not yet elapsed, the process flow returns to step S2.

The processes in steps S2 and S3 are then repeated until the operation detector 101 determines that the closing operation has ended in step S2 or determines that the prescribed time period Ta has elapsed in step S3.

If the operation detector 101 determines that the prescribed time period Ta has elapsed in step S3, the process flow proceeds to step S4.

In step S4, the opening-closing controller 104 turns ON the passenger's seat relay contact on the close side. Specifically, the opening-closing controller 104 turns ON the relay contact 81YUa via the driving circuit 82a.

As indicated in the timing chart in the left half in FIG. 12, the relay contact 81YUa is turned ON if the closing operation is performed to the passenger's seat sub switch 91a continuously for not less than the prescribed time period Ta and motor current is detected continuously. The automatic window system 1 then comes into the state depicted in FIG. 14. Motor current does not change in route in this case, so that the closing motion of the front passenger's seat window continues.

As depicted in FIG. 15, even when the closing operation to the passenger's seat sub switch 91a subsequently ends and the contact 91Ua is turned OFF, the opening-closing controller 104 keeps the state where the relay contact 81YUa is ON via the driving circuit 82a. Accordingly, current flows from the power supply B to ground via the main relay 14, the terminal a of the relay contact 81YUa, the terminal b of the contact 91Ua, the motor 13a, the terminal b of the contact 91Da, the terminal b of the relay contact 81YDa, and the

22

resistor R21a. This causes motor current to continuously flow in the forward direction to the motor 13a, so as to continue the closing motion of the front passenger's seat window.

5 In step S5, the window position detector 102 determines whether or not the passenger's seat window is fully closed. Specifically, the window position detector 102 detects a position of the front passenger's seat window in the opening-closing direction in accordance with the ripple of motor 10 current at the motor 13a as described above. If the window position detector 102 determines that the front passenger's seat window has not been fully closed yet, the process flow proceeds to step S6.

In step S6, the operation detector 101 determines whether 15 or not the automatically closing motion is canceled. If the operation detector 101 determines that automatically closing motion is not canceled, the process flow returns to step S5.

The processes in steps S5 and S6 are then repeated until 20 the window position detector 102 determines that the passenger's seat window is fully closed in step S5 or the operation detector 101 determines that the automatically closing motion is canceled in step S6.

If the opening operation is performed to the passenger's seat main switch 33a or the passenger's seat sub switch 91a, 25 for example, the operation detector 101 determines that the automatically closing motion is canceled in step S6. The operation detector 101 determines that the automatically closing motion is canceled if the opening operation is performed to the passenger's seat main switch 33a and the 30 operation detector 101 detects that the contact 61Da is turned ON via the input circuit 62a, for example.

Alternatively, if the opening operation is performed to the passenger's seat sub switch 91a and the contact 91Da is turned ON as depicted in FIG. 16, the motor 13a has 35 subsequently equal potential at the both ends and motor current stops. The operation detector 101 thus determines that the automatically closing motion is canceled if the operation detector 101 detects that motor current at the motor 13a stops for not less than a predetermined time 40 period.

If the operation detector 101 determines that automatically closing motion is canceled, the process flow proceeds to step S7.

Alternatively, if the window position detector 102 determines 45 that the passenger's seat window is fully closed in step S5, the process flow proceeds to step S7.

In step S7, the opening-closing controller 104 turns OFF the passenger's seat relay contact on the close side. Specifically, the opening-closing controller 104 turns OFF the relay contact 81YUa via the driving circuit 82a. This stops motor 50 current to the motor 13a.

In this manner, the automatically closing motion of automatically fully closing the front passenger's seat window is achieved even if the closing operation to the passenger's seat 55 sub switch 91a ends, unless the closing operation is canceled halfway.

The window opening-closing process then ends.

If the operation detector 101 determines that the closing operation has ended in step S2, the processes from steps S3 60 to S7 are not executed and the window opening-closing process ends. This applies to a case where the closing operation to the passenger's seat sub switch 91a ends before the prescribed time period Ta elapses.

As indicated in the left half in FIG. 13, the relay contact 65 81YUa serving as the passenger's seat relay contact on the close side is kept OFF in this case. When the contact 91Ua is turned OFF along with end of the closing operation, motor

current to the motor **13a** stops and the closing operation to the front passenger's seat window stops.

If the detection value of the motor current at the motor **13a** is less than the threshold **Ia**, the operation detector **101** determines that the opening operation is performed in step **S1**. The process flow then proceeds to step **S8**.

The automatic window system **1** comes into the state depicted in FIG. 8 in this case, and motor current flows in the backward direction to the motor **13a** to start the opening motion of the front passenger's seat window.

In step **S8**, the operation detector **101** determines whether or not the opening operation is performed continuously. For example, if the detection value of the motor current at the motor **13a** is not less than a predetermined threshold **Ib**, the operation detector **101** determines that the opening operation is performed continuously. The process flow then proceeds to step **S9**. This threshold **Ib** can be set to be smaller than the minimum value of the motor current flowing to the motor **13a** when the front passenger's seat window is opening in the stable state.

As in step **S2**, the operation detector **101** determines whether or not the prescribed time period **Ta** has elapsed in step **S9**. If the operation detector **101** determines that the prescribed time period **Ta** has not yet elapsed, the process flow returns to step **S8**.

The processes in steps **S8** and **S9** are then repeated until the operation detector **101** determines that the opening operation has ended in step **S8** or determines that the prescribed time period **Ta** has elapsed in step **S9**.

If the operation detector **101** determines that the prescribed time period **Ta** has elapsed in step **S9**, the process flow proceeds to step **S10**.

In step **S10**, the opening-closing controller **104** turns ON the passenger's seat relay contact on the open side.

Specifically, the opening-closing controller **104** turns ON the relay contact **81YDa** via the driving circuit **82a**.

As indicated in the timing chart in the right half in FIG. 12, the relay contact **81YDa** is turned ON if the opening operation is performed to the passenger's seat sub switch **91a** continuously for not less than the prescribed time period **Ta** and motor current is continuously detected. The automatic window system **1** then comes into the state depicted in FIG. 17. Motor current does not change in route in this case, so that the opening motion of the front passenger's seat window continues.

As depicted in FIG. 18, even when the opening operation to the passenger's seat sub switch **91a** subsequently ends and the contact **91Da** is turned OFF, the opening-closing controller **104** keeps the state where the relay contact **81YDa** is ON via the driving circuit **82a**. Accordingly, current flows from the power supply **B** to ground via the main relay **14**, the terminal **a** of the relay contact **81YDa**, the terminal **b** of the contact **91Da**, the motor **13a**, the terminal **b** of the contact **91Ua**, the terminal **b** of the relay contact **81YUa**, and the resistor **R21a**. This causes motor current to continuously flow in the backward direction to the motor **13a**, so as to continue the opening motion of the front passenger's seat window.

In step **S11**, the window position detector **102** determines whether or not the passenger's seat window is fully opened. Specifically, the window position detector **102** detects a position of the front passenger's seat window in the opening-closing direction in accordance with the ripple of motor current at the motor **13a** as described above. If the window position detector **102** determines that the front passenger's seat window has not been fully opened yet, the process flow proceeds to step **S12**.

In step **S12**, the operation detector **101** determines whether or not the automatically opening motion is canceled. If the operation detector **101** determines that the automatically opening motion is not canceled, the process flow returns to step **S11**.

The processes in steps **S11** and **S12** are then repeated until the window position detector **102** determines that the passenger's seat window is fully opened in step **S11** or the operation detector **101** determines that the automatically opening motion is canceled in step **S12**.

If the closing operation is performed to the passenger's seat main switch **33a** or the passenger's seat sub switch **91a**, for example, the operation detector **101** determines that the automatically opening motion is canceled in step **S12**. The operation detector **101** determines that the automatically opening motion is canceled if the closing operation is performed to the passenger's seat main switch **33a** and the operation detector **101** detects that the contact **61Ua** is turned ON via the input circuit **62a**, for example.

Alternatively, if the closing operation is performed to the passenger's seat sub switch **91a** and the contact **91Ua** is turned ON as depicted in FIG. 19, the motor **13a** has subsequently equal potential at the both ends and motor current stops. The operation detector **101** thus determines that the automatically opening motion is canceled if the operation detector **101** detects that motor current at the motor **13a** stops for not less than a predetermined time period.

If the operation detector **101** determines that automatically opening motion is canceled, the process flow proceeds to step **S13**.

Alternatively, if the window position detector **102** determines that the passenger's seat window is fully opened in step **S11**, the process flow proceeds to step **S13**.

In step **S13**, the opening-closing controller **104** turns OFF the passenger's seat relay contact on the open side.

Specifically, the opening-closing controller **104** turns OFF the relay contact **81YDa** via the driving circuit **82a**. This stops motor current to the motor **13a**.

In this manner, the automatically opening motion of automatically fully opening the front passenger's seat window is achieved even if the opening operation to the passenger's seat sub switch **91a** stops, unless the opening operation is canceled halfway.

The window opening-closing process then ends. If the operation detector **101** determines that the opening operation has ended in step **S8**, the processes from steps **S9** to **S13** are not executed and the window opening-closing process ends. This applies to a case where the opening operation to the passenger's seat sub switch **91a** ends before the prescribed time period **Ta** elapses.

As indicated in the right half in FIG. 13, the relay contact **81YDa** serving as the passenger's seat relay contact on the open side is kept OFF in this case. When the contact **91Da** is turned OFF along with end of the opening operation, motor current to the motor **13a** stops and the opening motion of the front passenger's seat window stops.

As described above, the closing operation or the opening operation is performed to the passenger's seat sub switch **91a** continuously for not less than the prescribed time period **Ta**, so as to achieve the automatic operation to the front passenger's seat window.

The automatic operation to the rear right passenger's seat window and the rear left passenger's seat window can be achieved by similarly operating the passenger's seat sub switches **91b** and **91c**.

{Second Achievement Method}

The second achievement method for the automatic operation to the passenger's seat window with the passenger's seat sub switch 91 will be described next with reference to FIGS. 20 to 24. According to the second achievement method, the passenger's seat sub switch 91 is operated continuously for a period not less than a prescribed time period Tb and less than a prescribed time period Tc (hereinafter, referred to as short push operation) to achieve the automatic operation. The prescribed time period Tb is set to be long enough to prevent erroneous detection that the operation is performed by lightly touching the passenger's seat sub switch 91 with no intention, for example. The prescribed time period Tb can be set to zero. The prescribed time period Tc is set to be longer than the prescribed time period Tb and shorter than the prescribed time period Ta adopted in the first achievement method. The prescribed time period Tc can be set such that a user can recognize as having operated the passenger's seat sub switch 91a intentionally for a short period of time.

A window opening-closing process executed by the automatic window system 1 with the passenger's seat sub switch 91 according to a second embodiment will now be described with reference to the flowchart in FIG. 20 and the timing charts in FIGS. 21 and 22. This window opening-closing process starts when the closing operation or the opening operation is performed to any one of the passenger's seat sub switches 91a to 91c and the operation detector 101 detects that the operation is performed.

FIGS. 21 and 22 are timing charts similar to those in FIGS. 12 and 13. A timing chart for the automatically closing operation is indicated in the left half divided by the dotted lines in FIG. 21, whereas a timing chart for the automatically opening operation is indicated in the right half divided by the dotted lines in FIG. 21. A timing chart for the manually closing operation is indicated in the left half divided by the dotted lines in FIG. 22, whereas a timing chart for the manually opening operation is indicated in the right half divided by the dotted lines in FIG. 22.

Exemplified below is a case of opening and closing the front passenger's seat window with the passenger's seat sub switch 91a. The passenger's seat in the flowchart in FIG. 20 and the timing charts in FIGS. 21 and 22 mainly refer to the front passenger's seat in the following description.

As in step S1 in FIG. 11, the operation detector 101 determines whether or not the closing operation is performed in step S51. If the operation detector 101 determines that closing operation is performed, the process flow proceeds to step S52.

As in step S2 in FIG. 11, the operation detector 101 determines whether or not the closing operation is performed continuously in step S52. This determination is repeated until the operation detector 101 determines that the closing operation has ended. If the operation detector 101 determines that the closing operation has ended, the process flow proceeds to step S53.

The automatic window system 1 is kept in the state depicted in FIG. 7 until the operation detector 101 determines that the closing operation has ended. Motor current flows in the forward direction to the motor 13a to achieve the closing motion of the front passenger's seat window. The closing motion of the front passenger's seat window stops along with end of the closing operation.

In step S53, the operation detector 101 determines whether or not the prescribed time period Tb≤the operation time period<the prescribed time period Tc is satisfied. The operation time period herein is duration of the closing

operation from detection of the closing operation to the passenger's seat sub switch 91a to determination of end of the closing operation in step S52. If the operation detector 101 determines that the prescribed time period Tb≤the operation time period<the prescribed time period Tc is satisfied, the process flow proceeds to step S54.

As in step S4 in FIG. 11, the passenger's seat relay contact on the close side is turned ON in step S54. As indicated in the timing chart in the left half in FIG. 21 as well as depicted in FIG. 23, the relay contact 81YUa is turned ON after end of the closing operation if the closing operation is performed to the passenger's seat sub switch 91a continuously for a period not less than the prescribed time period Tb and less than the prescribed time period Tc. Accordingly, as depicted in FIG. 23, current flows from the power supply B to ground via the main relay 14, the terminal a of the relay contact 81YUa, the terminal b of the contact 91Ua, the motor 13a, the terminal b of the contact 91Da, the terminal b of the relay contact 81YDa, and the resistor R21a. This causes motor current to restart flowing in the forward direction to the motor 13a, so as to restart the closing motion of the front passenger's seat window.

It is possible to appropriately set a time period from end of the closing operation to the passenger's seat sub switch 91a to turning ON the relay contact 81YUa.

Subsequently in steps S55 to S57, processes similar to the processes from steps S5 to S7 in FIG. 11 are executed and the window opening-closing process ends. In this manner, the automatically closing motion of automatically fully closing the front passenger's seat window is achieved if the closing operation to the passenger's seat sub switch 91a ends before the prescribed time period Tc elapses, unless the closing operation is canceled halfway.

If the operation detector 101 determines that the operation time period<the prescribed time period Tb or the operation time period≥the prescribed time period Tc is satisfied in step S53, the processes from steps S54 to S57 are not executed and the window opening-closing process ends.

As indicated in the left half in FIG. 22, the relay contact 81YUa serving as the passenger's seat relay contact on the close side is kept OFF in this case. The front passenger's seat window is thus closed only while the closing operation is performed to the passenger's seat sub switch 91a (manually closing motion).

If the operation detector 101 determines that the opening operation is performed in step S51, the process flow proceeds to step S58.

As in step S8 in FIG. 11, the operation detector 101 determines whether or not the opening operation is performed continuously in step S58. This determination is repeated until the operation detector 101 determines that the opening operation has ended. If the operation detector 101 determines that the opening operation has ended, the process flow proceeds to step S59.

The automatic window system 1 is kept in the state depicted in FIG. 8 until the operation detector 101 determines that the opening operation has ended. Motor current flows in the backward direction to the motor 13a to achieve the opening motion of the front passenger's seat window. The opening motion of the front passenger's seat window stops along with end of the opening operation.

As in step S53, the operation detector 101 determines whether or not the prescribed time period Tb≤the operation time period<the prescribed time period Tc is satisfied in step S59. If the operation detector 101 determines that the prescribed time period Tb≤the operation time period<the prescribed time period Tc is satisfied, the process flow

proceeds to step S60. The operation time period is duration of the opening operation from detection of the opening operation to the passenger's seat sub switch 91a to determination of end of the opening operation in step S58.

As in step S10 in FIG. 11, the passenger's seat relay contact on the open side is turned ON in step S60. As indicated in the timing chart in the right half in FIG. 21 as well as depicted in FIG. 24, the relay contact 81YDa is turned ON after end of the opening operation if the opening operation is performed to the passenger's seat sub switch 91a continuously for a period not less than the prescribed time period Tb and less than the prescribed time period Tc. Accordingly, as depicted in FIG. 24, current flows from the power supply B to ground via the main relay 14, the terminal a of the relay contact 81YDa, the terminal b of the contact 91Da, the motor 13a, the terminal b of the contact 91Ua, the terminal b of the relay contact 81YUa, and the resistor R21a. This causes motor current to restart flowing in the backward direction to the motor 13a, so as to restart the opening motion of the front passenger's seat window.

It is possible to appropriately set a time period from end of the opening operation to the passenger's seat sub switch 91a to turning ON the relay contact 81YDa.

Subsequently in steps S61 to S63, processes similar to the processes from steps S11 to S13 in FIG. 11 are executed and the window opening-closing process ends. In this manner, the automatically opening motion of automatically fully opening the front passenger's seat window is achieved if the opening operation to the passenger's seat sub switch 91a ends before the prescribed time period Tc elapses, unless the opening operation is canceled halfway.

If the operation detector 101 determines that the operation time period < the prescribed time period Tb or the operation time period ≥ the prescribed time period Tc is satisfied in step S59, the processes from steps S60 to S63 are not executed and the window opening-closing process ends.

As indicated in the right half in FIG. 22, the relay contact 81YDa serving as the passenger's seat relay contact on the open side is kept OFF in this case. The front passenger's seat window is thus opened only while the opening operation is performed to the passenger's seat sub switch 91a (manually opening motion).

As described above, the closing operation or the opening operation is performed to the passenger's seat sub switch 91a continuously for a period not less than the prescribed time period Tb and less than the prescribed time period Tc, so as to achieve the automatic operation to the front passenger's seat window.

The automatic operation to the rear right passenger's seat window and the rear left passenger's seat window can be achieved by similarly operating the passenger's seat sub switches 91b and 91c.

{Third Achievement Method}

The third achievement method for the automatic operation to the passenger's seat window with the passenger's seat sub switch 91 will be described next with reference to FIGS. 25 to 35. The third achievement method is achieved by modifying the second achievement method, and similarly to the second achievement method, the passenger's seat sub switch 91 is operated continuously for a period not less than the prescribed time period Tb and less than the prescribed time period Tc (e.g. short push operation) to achieve the automatic operation.

Specifically, according to the second achievement method, there is a motor stop period after end of the operation to the passenger's seat sub switch 91 during the automatic operation as indicated in FIG. 21. Accordingly,

the passenger's seat window is opened or closed discontinuously. The third achievement method is provided to eliminate such discontinuous motion of the passenger's seat window.

5 A window opening-closing process executed by the automatic window system 1 with the passenger's seat sub switch 91 according to a third embodiment will now be described with reference to the flowchart in FIG. 25 and the timing charts in FIGS. 26 and 27. This window opening-closing process starts when the closing operation or the opening operation is performed to any one of the passenger's seat sub switches 91a to 91c and the operation detector 101 detects that the operation is performed.

FIGS. 26 and 27 are timing charts similar to those in 15 FIGS. 12, 13, 21, and 22. A timing chart for the automatically closing operation is indicated in the left half divided by the dotted lines in FIG. 26, whereas a timing chart for the automatically opening operation is indicated in the right half divided by the dotted lines in FIG. 26. A timing chart for the 20 manually closing operation is indicated in the left half divided by the dotted lines in FIG. 27, whereas a timing chart for the manually opening operation is indicated in the right half divided by the dotted lines in FIG. 27.

Exemplified below is a case of opening and closing the 25 front passenger's seat window with the passenger's seat sub switch 91a. The passenger's seat in the flowchart in FIG. 25 and the timing charts in FIGS. 26 and 27 mainly refer to the front passenger's seat in the following description.

As in step S1 in FIG. 11, the operation detector 101 30 determines whether or not the closing operation is performed in step S101. If the operation detector 101 determines that closing operation is performed, the process flow proceeds to step S102.

In this case, the automatic window system 1 comes into 35 the state depicted in FIG. 7, and motor current flows in the forward direction to the motor 13a to start the closing motion of the front passenger's seat window.

As in step S2 in FIG. 11, the operation detector 101 40 determines whether or not the closing operation is performed continuously in step S102. If the operation detector 101 determines that closing operation is performed continuously, the process flow proceeds to step S103.

In step S103, the operation detector 101 determines 45 whether or not the prescribed time period Tb has elapsed. If the operation detector 101 determines that the prescribed time period Tb has not yet elapsed, the process flow returns to step S102.

The processes in steps S102 and S103 are then repeated 50 until the operation detector 101 determines that the closing operation has ended in step S102 or determines that the prescribed time period Tb has elapsed in step S103.

If the operation detector 101 determines that the prescribed time period Tb has elapsed in step S103, the process flow proceeds to step S104.

55 As in step S4 in FIG. 11, the passenger's seat relay contact on the close side is turned ON in step S104. Specifically, the relay contact 81YUa is turned ON as depicted in FIG. 28. Motor current does not change in route in this case, so that the closing motion of the front passenger's seat window continues.

In step S105, the operation detector 101 determines 60 whether or not the prescribed time period Tc has elapsed. If the operation detector 101 determines that the prescribed time period Tc has not yet elapsed, the process flow proceeds to step S106.

As in step S2 in FIG. 11, the operation detector 101 65 determines whether or not the closing operation is per-

formed continuously in step S106. If the operation detector 101 determines that closing operation is performed continuously, the process flow returns to step S105.

The processes in steps S105 and S106 are then repeated until the operation detector 101 determines that the prescribed time period Tc has elapsed in step S105 or determines that the closing operation has ended in step S106.

While the closing operation to the passenger's seat sub switch 91a ends, the terminal c and the terminal a of the contact 91Ua are disconnected from each other, and the terminal c and the terminal b are connected to each other in step S106, the contact 91Ua is in a contactless state and motor current stops instantaneously as depicted in FIG. 29. If the contact 91Ua is thereafter turned OFF as depicted in FIG. 30, current flows from the power supply B to ground via the main relay 14, the terminal a of the relay contact 81YUa, the terminal b of the contact 91Ua, the motor 13a, the terminal b of the contact 91Da, the terminal b of the relay contact 81YDa, and the resistor R21a. In other words, motor current restarts flowing in the forward direction to the motor 13a.

As indicated in the left half in FIG. 26, motor current at the motor 13a thus decreases instantaneously after end of the closing operation and then returns to the stable state. If the operation detector 101 detects such brief decrease in motor current, the operation detector 101 determines that the closing operation has ended. The process flow then proceeds to step S107.

Thereafter, as indicated in the left half in FIG. 26, the passenger's seat relay contact 81YUa serving as the passenger's seat relay contact on the close side is kept ON even after the prescribed time period Tc elapses.

Subsequently in steps S107 to S109, processes similar to the processes from steps S5 to S7 in FIG. 11 are executed and the window opening-closing process ends. In this manner, the automatically closing motion of automatically fully closing the front passenger's seat window is achieved if the closing operation to the passenger's seat sub switch 91a ends before the prescribed time period Tc elapses, unless the closing operation is canceled halfway. Motor current may instantaneously stop at end of the closing operation to the passenger's seat sub switch 91a and the front passenger's seat window may move slowly. Such slow motion can be made to continue only briefly so that no user cares.

If the operation detector 101 determines that the prescribed time period Tc has elapsed in step S105, the processes from steps S106 to S108 are not executed and the process flow proceeds to step S109.

As in step S7 in FIG. 11, the passenger's seat relay contact on the close side is turned OFF in step S109 and the window opening-closing process ends. As indicated in the left half in FIG. 27, if the closing operation to the passenger's seat sub switch 91a is performed continuously for not less than the prescribed time period Tc, the relay contact 81YUa is turned OFF as depicted in FIG. 31. Motor current does not change in route in this case, so that the closing motion of the front passenger's seat window continues.

If the closing operation to the passenger's seat sub switch 91a then ends and the contact 91Ua is turned OFF, motor current to the motor 13a stops and the closing motion of the front passenger's seat window stops.

If the operation detector 101 determines that the closing operation has ended in step S102, in other words, if the closing operation ends before the prescribed time period Tb elapses, the processes from steps S103 to S109 are not executed and the window opening-closing process ends.

If the operation detector 101 determines that the opening operation is performed in step S101, the process flow proceeds to step S110.

As in step S8 in FIG. 11, the operation detector 101 determines whether or not the opening operation is performed continuously in step S110. If the operation detector 101 determines that the opening operation is performed continuously, the process flow proceeds to step S111.

As in step S103, the operation detector 101 determines whether or not the prescribed time period Tb has elapsed in step S111. If the operation detector 101 determines that the prescribed time period Tb has not yet elapsed, the process flow returns to step S110.

The processes in steps S110 and S111 are then repeated until the operation detector 101 determines that the opening operation has ended in step S110 or determines that the prescribed time period Tb has elapsed in step S111.

If the operation detector 101 determines that the prescribed time period Tb has elapsed in step S111, the process flow proceeds to step S112.

As in step S10 in FIG. 11, the passenger's seat relay contact on the open side is turned ON in step S112. Specifically, the relay contact 81YDa is turned ON as depicted in FIG. 32. Motor current does not change in route in this case, so that the opening motion of the front passenger's seat window continues.

As in step S105, the operation detector 101 determines whether or not the prescribed time period Tc has elapsed in step S113. If the operation detector 101 determines that the prescribed time period Tc has not yet elapsed, the process flow proceeds to step S114.

As in step S8 in FIG. 11, the operation detector 101 determines whether or not the opening operation is performed continuously in step S114. If the operation detector 101 determines that the opening operation is performed continuously, the process flow returns to step S113.

The processes in steps S113 and S114 are then repeated until the operation detector 101 determines that the prescribed time period Tc has elapsed in step S113 or determines that the opening operation has ended in step S114.

While the opening operation to the passenger's seat sub switch 91a ends, the terminal c and the terminal a of the contact 91Da are disconnected from each other, and the terminal c and the terminal b are connected to each other in step S114, the contact 91Da is in the contactless state and motor current stops instantaneously as depicted in FIG. 33. If the contact 91Da is thereafter turned OFF as depicted in FIG. 34, current flows from the power supply B to ground via the main relay 14, the terminal a of the relay contact 81YDa, the terminal b of the contact 91Da, the motor 13a, the terminal b of the contact 91Ua, the terminal b of the relay contact 81YUa, and the resistor R21a. In other words, motor current restarts flowing in the backward direction to the motor 13a.

As indicated in the right half in FIG. 26, motor current at the motor 13a thus decreases instantaneously after end of the opening operation and then returns to the stable state. If the operation detector 101 detects such brief decrease in motor current, the operation detector 101 determines that the opening operation has ended. The process flow then proceeds to step S115.

Thereafter, as indicated in the right half in FIG. 26, the passenger's seat relay contact 81YDa serving as the passenger's seat relay contact on the open side is kept ON even after the prescribed time period Tc elapses.

Subsequently in steps S115 to S117, processes similar to the processes from steps S11 to S13 in FIG. 11 are executed

and the window opening-closing process ends. In this manner, the automatically opening motion of automatically fully opening the front passenger's seat window is achieved if the opening operation to the passenger's seat sub switch 91a ends before the prescribed time period Tc elapses, unless the opening operation is canceled halfway. Motor current may instantaneously stop at end of the opening operation to the passenger's seat sub switch 91a and the front passenger's seat window may move slowly. Such slow motion can be made to continue only briefly so that no user cares.

If the operation detector 101 determines that the prescribed time period Tc has elapsed in step S113, the processes from steps S114 to S116 are not executed and the process flow proceeds to step S117.

As in step S13 in FIG. 11, the passenger's seat relay contact on the open side is turned OFF in step S117 and the window opening-closing process ends. As indicated in the right half in FIG. 27, if the opening operation to the passenger's seat sub switch 91a is performed continuously for not less than the prescribed time period Tc, the relay contact 81YDa is turned OFF as depicted in FIG. 35. Motor current does not change in route in this case, so that the closing motion of the front passenger's seat window continues.

If the opening operation to the passenger's seat sub switch 91a then ends and the contact 91Da is turned OFF, motor current to the motor 13a stops and the opening motion of the front passenger's seat window stops.

If the operation detector 101 determines that the opening operation has ended in step S110, in other words, if the opening operation ends before the prescribed time period Tb elapses, the processes from steps S111 to S117 are not executed and the window opening-closing process ends.

As described above, the closing operation or the opening operation is performed to the passenger's seat sub switch 91a continuously for a period not less than the prescribed time period Tb and less than the prescribed time period Tc, so as to achieve the automatic operation to the front passenger's seat window. Also achieved is prevention of discontinuous opening and closing of the front passenger's seat window.

The automatic operation to the rear right passenger's seat window and the rear left passenger's seat window can be achieved by similarly operating the passenger's seat sub switches 91b and 91c.

<2. Modification Examples>

Described below are modification examples of one or more embodiments according to the disclosure.

The above description exemplifies the case where there are the three passenger's seat windows, while the number of passenger's seat windows can be set optionally. The numbers of the motors 13, the passenger's seat units 22, the passenger's seat main switches 33, and the passenger's seat control circuits 35 can be increased or decreased in accordance with the number of the passenger's seat windows.

The main relay 14 can be replaced with a manual switch or the like, or the ignition switch 16 can be provided directly.

The above description exemplifies the case where the prescribed time periods Ta to Tc spent for detection of the automatically closing operation and the automatically opening operation are equally set for both the automatically closing operation and the automatically opening operation. Alternatively, the prescribed time periods Ta to Tc can be set differently for the automatically closing operation and the automatically opening operation.

The methods of detecting the automatically closing operation and the automatically opening operation are not necessary the same. For example, the automatically closing operation can be determined as having been performed if the closing operation to the passenger's seat sub switch 91 continues for not less than the prescribed time period Ta.

5 Furthermore, the automatically opening operation can be determined as having been performed if the opening operation to the passenger's seat sub switch 91 continues for not less than the prescribed time period Tb and less than the prescribed time period Tc.

10 The positions of the resistors (motor current detectors) configured to detect motor current at the motors 13 are not limited to the positions mentioned earlier. For example, a resistor can be provided between the terminal b of the relay contact 81YUa and ground, another resistor can be provided

15 between the terminal b of the relay contact 81YDa and ground, and the resistors can be each connected with an amplifier circuit, so as to enable detection of motor current at the motor 13a. Alternatively, a resistor can be provided between the terminal c of the relay contact 81YUa and the

20 terminal b of the relay contact 91Ua, another resistor can be provided between the terminal c of the relay contact 81YDa and the terminal b of the relay contact 91Da, and the resistors can be each connected with an amplifier circuit, so as to enable detection of motor current at the motor 13a. In

25 these manners, the resistors can be provided anywhere on the route of current flowing to the passenger's seat motor 13.

Motor current at each of the motors can be detected in accordance with a method other than the above method of measuring voltage at the both ends of the resistor.

30 The disclosure is applicable to a vehicle of any type provided with an automatic window function.

35 Embodiments of the invention should not be limited to those embodiments described above but can be modified variously within the range not departing from the gist of the invention.

The invention claimed is:

1. A window opening-closing control system configured to control opening and closing a window at a driver's seat and a window at a passenger's seat other than the driver's seat in a vehicle, the window opening-closing control system comprising:

a passenger's seat unit provided at the passenger's seat; and

45 a window opening-closing control apparatus provided at the driver's seat and configured to control a driver's seat motor configured to open and close the window at the driver's seat and a passenger's seat motor configured to open and close the window at the passenger's seat;

the passenger's seat unit including:

a momentary passenger's seat sub switch having a first contact operated to close the window at the passenger's seat and a second contact operated to open the window at the passenger's seat;

55 the first contact including:

a first common terminal connected to a first end of the passenger's seat motor;

a first normally opened terminal connected to a positive electrode of a power supply of the vehicle via a wire, and connected to the first common terminal in response to closing operation for closing the window at the passenger's seat; and

60 a first normally closed terminal;

the second contact including:

a second common terminal connected to a second end of the passenger's seat motor;

33

- a second normally opened terminal connected to the positive electrode of the power supply via the wire, and connected to the second common terminal in response to opening operation for opening the window at the passenger's seat; and
- a second normally closed terminal;
- the window opening-closing control apparatus including:
- a driver's seat main switch operated to open and close the window at the driver's seat;
- a passenger's seat main switch having a third contact 10 operated to close the window at the passenger's seat and a fourth contact operated to open the window at the passenger's seat, the passenger's seat main switch operated to open and close the window at the passenger's seat;
- a motor current detector configured to detect current flowing to the passenger's seat motor;
- a first relay circuit unit including a first common relay terminal connected to the first normally closed terminal, a first normally opened relay terminal connected to the positive electrode of the power supply, and a first 20 normally closed relay terminal connected to ground;
- a second relay circuit unit including a second common relay terminal connected to the second normally closed terminal, a second normally opened relay terminal connected to the positive electrode of the power supply, and a second normally closed relay terminal connected to ground;
- an operation detector configured to detect operation to the passenger's seat sub switch in accordance with motor current detected by the motor current detector; and
- an opening-closing controller configured to control the first relay circuit unit and the second relay circuit unit in accordance with the operation to the passenger's seat sub switch;
- wherein the operation detector detects whether the closing operation or the opening operation is performed to the passenger's seat sub switch in accordance with an amount of the motor current and detects duration of the operation to the passenger's seat sub switch, and
- wherein the opening-closing controller controls the first relay circuit unit or the second relay circuit unit to execute automatic motion of automatically closing or opening the window at the passenger's seat in accordance with the duration of the operation to the passenger's seat sub switch.
2. The window opening-closing control system according to claim 1, wherein the operation detector controls the first relay circuit unit or the second relay circuit unit to execute the automatic motion if the duration of the operation to the passenger's seat sub switch is less than a predetermined first prescribed time period.
3. The window opening-closing control system according to claim 2,
- wherein if the operation detector detects that the duration of the closing operation to the passenger's seat sub switch is not less than a predetermined second prescribed time period shorter than the first prescribed time period and less than the first prescribed time period, the opening-closing controller connects the first common relay terminal and the first normally opened relay terminal for the second prescribed time period and keeps the connection for more than the first prescribed time period,
- wherein if the operation detector detects that the duration of the closing operation to the passenger's seat sub switch is not less than the first prescribed time period,

34

- the opening-closing controller connects the first common relay terminal and the first normally opened relay terminal for the second prescribed time period and subsequently switches to connect the first common relay terminal to the first normally closed relay terminal for the first prescribed time period,
- wherein if the operation detector detects that the duration of the opening operation to the passenger's seat sub switch is not less than a predetermined second prescribed time period shorter than the first prescribed time period and less than the first prescribed time period, the opening-closing controller connects the second common relay terminal and the second normally opened relay terminal for the second prescribed time period and keeps the connection for more than the first prescribed time period, and
- wherein if the operation detector detects that the duration of the opening operation to the passenger's seat sub switch is not less than the first prescribed time period, the opening-closing controller connects the second common relay terminal and the second normally opened relay terminal for the second prescribed time period and subsequently switches to connect the second common relay terminal to the second normally closed relay terminal for the first prescribed time period.
4. The window opening-closing control system according to claim 2, wherein the opening-closing controller connects the first common relay terminal and the first normally opened relay terminal if the closing operation to the passenger's seat sub switch ends before the first prescribed time period elapses, and the opening-closing controller connects the second common relay terminal and the second normally opened relay terminal if the opening operation to the passenger's seat sub switch ends before the first prescribed time period elapses.
5. The window opening-closing control system according to claim 1, wherein the opening-closing controller controls the first relay circuit unit or the second relay circuit unit to execute the automatic motion if the duration of the operation to the passenger's seat sub switch is more than a predetermined third prescribed time period.
6. The window opening-closing control system according to claim 5, wherein the opening-closing controller connects the first common relay terminal and the first normally opened relay terminal if the closing operation to the passenger's seat sub switch continues for not less than the third prescribed time period and keeps the connection between the first common relay terminal and the first normally opened relay terminal after the closing operation ends, and the opening-closing controller connects the second common relay terminal and the second normally opened relay terminal if the opening operation to the passenger's seat sub switch continues for not less than the first prescribed time period and keeps the connection between the second common relay terminal and the second normally opened relay terminal after the opening operation ends.
7. The window opening-closing control system according to claim 1, wherein the operation detector detects whether the closing operation or the opening operation is performed to the passenger's seat sub switch in accordance with the amount of the motor current.
8. A window opening-closing control apparatus connected to a passenger's seat unit provided at a passenger's seat other than a driver's seat in a vehicle, the passenger's seat unit including:

35

a momentary passenger's seat sub switch having a first contact operated to close a window at the passenger's seat and a second contact operated to open the window at the passenger's seat;

the first contact including:

a first common terminal connected to a first end of a passenger's seat motor configured to open and close the window at the passenger's seat;

a first normally opened terminal connected to a positive electrode of a power supply of the vehicle via a wire, and connected to the first common terminal in response to closing operation for closing the window at the passenger's seat; and

a first normally closed terminal;

the second contact including:

a second common terminal connected to a second end of the passenger's seat motor;

a second normally opened terminal connected to the positive electrode of the power supply via the wire, and connected to the second common terminal in response to opening operation for opening the window at the passenger's seat; and

a second normally closed terminal;

the window opening-closing control apparatus provided at the driver's seat in the vehicle and configured to control a driver's seat motor configured to open and close a window at the driver's seat and the passenger's seat motor;

the window opening-closing control apparatus comprising:

a driver's seat main switch operated to open and close the window at the driver's seat;

a passenger's seat main switch having a third contact operated to close the window at the passenger's seat and a fourth contact operated to open the window at the

5

10

15

20

25

30

36

passenger's seat, the passenger's seat main switch operated to open and close the window at the passenger's seat;

a motor current detector configured to detect current flowing to the passenger's seat motor;

a first relay circuit unit including a first common relay terminal connected to the first normally closed terminal, a first normally opened relay terminal connected to the positive electrode of the power supply, and a first normally closed relay terminal connected to ground;

a second relay circuit unit including a second common relay terminal connected to the second normally closed terminal, a second normally opened relay terminal connected to the positive electrode of the power supply, and a second normally closed relay terminal connected to ground;

an operation detector configured to detect operation to the passenger's seat sub switch in accordance with motor current detected by the motor current detector; and

an opening-closing controller configured to control the first relay circuit unit and the second relay circuit unit in accordance with the operation to the passenger's seat sub switch;

wherein the operation detector detects whether the closing operation or the opening operation is performed to the passenger's seat sub switch in accordance with an amount of the motor current and

detects duration of the operation to the passenger's seat sub switch, and the opening-closing controller controls the first relay circuit unit or the second relay circuit unit to execute automatic motion of automatically closing or opening the window at the passenger's seat in accordance with the duration of the operation to the passenger's seat sub switch.
